UNITED STATES PATENT OFFICE.

MAX E. CRANDALL, OF KINGFISHER, OKLAHOMA.

AUTOMATIC CUT-OFF FOR CISTERNS.

Application filed January 26, 1925. Serial No. 4,894.

To all whom it may concern:

Be it known that I, MAX E. CRANDALL, a citizen of the United States, residing at Kingfisher, in the county of Kingfisher and State of Oklahoma, have invented certain new and useful Improvements in Automatic Cut-Offs for Cisterns, of which the following is a specification.

My invention relates to means for collecting rain water in cisterns and has special reference to the means whereby the flow of water may be directed to a waste pipe until all of the dirt or other accumulations upon a roof have been carried away and then automatically directed into the cistern. The object of the invention is to provide a simple device of compact form which will operate positively to permit flow to one side for a predetermined period of time and then automatically direct it to the opposite side. Another object of the invention is to provide a float controlled cut-off which will be inactive during part of the time the water is running and will then actuate the cut-off to divert the flow and hold the cut-off in the latter position until manually reset. These stated objects, and other objects which will incidentally appear in the course of the following description, are attained in such a mechanism as is illustrated in the accompanying drawing, and the invention resides in certain novel features which will be particularly pointed out in the appended claims.

In the drawing:

Fig. 1 is an elevation, partly broken away and in section, of one embodiment of my invention;

Fig. 2 is an elevation of the device viewed from the side opposite that seen in Fig. 1, the near wall of the cut-off tank being removed;

Fig. 3 is a transverse section on the line 3-3 of Fig. 1, and

Fig. 4 is a detail perspective view of the clamp whereby the controlling floats are attached to the cut-off shaft.

In the drawing, the reference numeral 1 indicates a portion of the side of a building, and 2 a portion of a down spout leading from the roof of the building. In carrying out my invention, the end of the down spout 2 is fitted in the upper central branch 3 of an inverted Y-shaped coupling having one outlet 4 adapted to discharge upon the ground or be connected with a sewer or otherwise arranged to carry off waste water while the

other terminal 5 is connected with a pipe 6 leading to the cistern. The said coupling is secured upon the outer side of a cut-off tank 7 which is secured to the side of the building and has a removable cover 8 fitted upon its upper end, a clean-out plug 9 being provided in the bottom of the tank and a very small drain opening or perforation 10 being provided in the outer side thereof near the bottom. Near the upper end of the tank 7 an opening 11 is formed through the outer wall thereof, and this opening 11 registers with a similar opening 12 in the inner wall of the upright portion 3 of the coupling, a cut-off plate or damper 13 being pivotally mounted within the tank adjacent the opening 11 and adapted to extend over the same and cut-off the flow therethrough in an obvious manner. Within the branch 3 of the Y coupling immediately below the opening 12, I provide a trough 14 which consists of a collar or ring having its lower end fitting in close contact with the inner surface of the branch 3 while its upper portion is spaced inwardly from the wall of said branch, as shown at 15 in Fig. 3, whereby an annular collecting space is provided to receive a small portion of the water flowing through the down spout and direct the same into and through the openings 12 and 11, the offset or shoulder 16 of the collar being inclined toward the opening 12, as clearly shown in Fig. 3. Above the trough or collar, a tubular screen 17 is secured within the branch 3, the upper end of this screen being of a proper diameter to fit snugly and closely to the inner surface of the branch, while its lower end is of less diameter and fits within the upper end of the collar or trough 14, the screen being tapered so that the greater vacuum of the water and any leaves, trash or other matter which may have collected upon the roof and which is washed down by the rain water will be permitted to pass through the coupling. At the junction of the discharge branches 4 and 5 of the coupling, a rock shaft 18 is journaled in the walls of the coupling and has one end extended into the tank 7 and there equipped with a crank arm 19. The cut-off valve 20 is secured to the rock shaft 18 and is in the form of a scoop or pan extending in both directions from the rock shaft so that it may extend entirely across either branch 4 or 5 of the coupling and thereby cut-off the flow into one coupling and direct it into the other branch.

Within the tank, I provide a pair of floats 21 and 22 which are carried by a bent arm 23 connected midway its ends with the crank 19 of the rock shaft 18. To connect the arm 23 with the rock shaft, I employ a pair of clamping plates 24 and 25, the upper plate 24 being flat throughout its extent and provided in one edge with a notch 26, as shown most clearly in Fig. 4, while the lower plate 25 is provided with a flange 27 along its outer edge having a notch 28 therein whereby the flange may receive the end of the rock shaft 18 and lie close against the outer side of the crank 19 which rests upon the plate 25 between the same and the plate 24. The plate 25 is also provided with a flange 29 along its inner edge which is provided with a notch 30 forming a continuation of the notch 26 in the plate 25 and so located as to register with the notch 26 in the upper clamping plate 24. The arm 23 is so bent as to provide branches which are disposed at an acute angle to each other and a central connecting portion which is adapted to extend between the clamping plates 24 and 25, lying against the flange 29, as shown in Fig. 4. Set screws 32 are inserted through and engaged in openings 33 provided therefor in the clamping plates so that, when the screws are turned home, the clamping plates will be firmly secured together against the crank 19 and the intermediate portion of the arm 23 with the clamping plate 24 resting upon the flanges 27 and 29 of the plate 25. The arm carrying the floats will thus be rigidly connected with the crank of the rock shaft so that any movement of the floats will be transmitted to the rock shaft and movement of the rock shaft will, of course, be transmitted to the arm 23 and the floats. It is also to be noted that the central portion of the float-carrying arm is disposed parallel with the crank of the rock shaft and the arm, therefore, stands at a right angle to the rock shaft with the floats at opposite sides of the axis of the rock shaft.

In use, the valve 20 is initially set, as shown in full lines in Fig. 1, so that, if there should be rain, the water flowing from the roof through the down spout will be directed into the waste discharge terminal 4 and the dust or other impurities which may have collected upon the roof will be carried away. The damper 13 is, of course, set in the position shown in Fig. 2 so that water may flow freely through the openings 12 and 11 into the tank 7. When a rain occurs, the water flowing through the down spout will, of course, fall upon the cut-off valve 20 and be deflected into the waste discharge 4 but a small portion of the water will pass through the screen 17 and tend to collect in the trough or space between the upper portion of the collar 14 and the wall of the branch 3

of the coupling. This water obviously will be deflected into and through the openings 12 and 11 and will tend to accumulate in the tank 7 but the accumulation will be slow inasmuch as there is a minute drainage 70 through the vent 10, and the rate of flow into the tank may be regulated by setting the damper 13 so as to uncover more or less of the opening 11. As the water rises in the tank, it will tend to lift the floats 21 and 22 75 but the lifting action of the water upon the lower float 22 will not be sufficient to overcome the dead-weight of the upper float 21 until the water level reaches the latter float, whereupon the floats will be raised as the 80 water level rises and the arm 23 will be rocked so as to turn the shaft 18 and thereby shift the cut-off valve to the position shown in dotted lines in Fig. 1, cutting off 85 the flow into the waste terminal 4 and directing it into the terminal 5 connected with the cistern. As the water level continues to rise, the upper float 21 will be carried past the vertical plane of the rock shaft 18 and assume the position shown in dotted lines in 90 Fig. 2, past the dead-center, so that its weight will serve to hold both floats in the raised position and the cut-off valve 20 will 95 continue to direct the water into the cistern even though the tank 7 should be filled and even after all the water has drained out from the vent 10. Of course, if the device should be operating in the daytime, the flow into the tank may be cut-off by setting the 100 damper 13 so as to entirely cover the opening 11.

From the foregoing description, taken in connection with the accompanying drawing, it will be seen that I have provided a very 105 simple and compact device whereby the flow of water will be directed into a waste pipe until all impurities have been washed away and then automatically directed into the cistern for use. The action of the cut-off valve is positive and cannot occur prematurely so as to direct water into the cistern before all the impurities have been washed away inasmuch as the floats do not rise gradually with the increase of water in the tank 110 but are inert until the water reaches the upper float. When the cut-off has been reversed, it will remain in the reverse position, directing flow into the cistern, notwithstanding the decrease of water in the tank inasmuch as the upper float will have been carried past the dead-center and will counter-balance any tendency of the lower float to drop.

The tank is of sufficient dimensions to 115 permit the floats and the float-carrying arm to be disposed at either side of the axis of the rock shaft accordingly as circumstances require the cistern to be connected with the right-hand or left-hand discharge terminal 120 of the Y coupling. To arrange the floats 125

in reversed position, relative to the position shown in the drawing, the set screws 32 are withdrawn so as to permit separation of the clamping plates 24 and 25 and the arm 5 23 is then rocked so that the intermediate portion thereof will pass through the notch 26 in the plate 24 instead of through the notch 31 in the plate 25, as shown, this shifting of the said arm bringing the floats into 10 position at the opposite side of the shaft and, of course, holding the crank 19 normally at an angle of ninety degrees to that illustrated. The operation of the device, when thus reversed, will be exactly the same as herein- 15 before described, except that the waste water will be directed through the discharge terminal 5 instead of through the terminal 4 and the terminal 4 will be connected with the cistern.

20 Having thus described the invention, I claim:

1. In an automatic cut-off for cisterns, the combination of a Y coupling connected with a down spout and having spaced discharge terminals, a tank disposed at the 25 side of the said coupling and in communication with the upper portion of the same, a trough within the coupling below and immediately adjacent the point of communication between the coupling and the tank, a screen secured within the coupling above the trough and having its lower end fitting within the bore of the trough, a cut-off mounted within the coupling at the junction 30 of the discharge terminals thereof, and float-controlled means within the tank for shifting said cut-off.

2. In an automatic cut-off for cisterns, the combination of a Y coupling connected 40 with a down spout and having an opening through its wall adjacent its upper end, a tank disposed at the side of the said coupling and having an opening through its wall registering with the said opening in the coupling, a damper within the tank controlling flow through said openings, a collar having its lower end secured to the inner surface of the coupling immediately below the opening therethrough and its upper end 45 spaced inwardly from the surface of the coupling, a tubular screen having its upper end secured to the wall of the coupling above the said collar and its lower end fitting within the bore of the collar, a cut-off within 50 the coupling at the junction of the discharge terminals thereof, and float-controlled means within the tank for shifting said cut-off.

3. In an automatic cut-off for cisterns, the combination of a Y coupling having its upper end connected with a down spout, a tank connected with the side of the said cou-

pling and having its upper portion in communication with the upper end of the same, a tiltable cut-off within the coupling at the junction of the discharge terminals thereof, 65 a float arm disposed within the tank and connected with said cut-off, and a pair of floats carried by the said arm, the arm having its end portions disposed at an acute angle and the floats being secured upon the 70 ends of the arms whereby one float will be disposed above the other float.

4. In an automatic cut-off for cisterns, the combination of a Y coupling having its upper end connected with a down spout and 75 having its lower end defining spaced discharge terminals, a rock shaft mounted in the coupling at the junction of the discharge terminals, a cut-off valve carried by the said rock shaft within the coupling, a tank connected with the coupling and in communication therewith at its upper end, one end of the shaft extending into the tank, a crank on the end of the shaft within the tank, a float arm connected with said crank, and 80 floats carried by the said arm and disposed in vertically spaced relation.

5. In an automatic cut-off for cisterns, the combination of a Y coupling having its upper end connected with a down spout and 90 having its lower end defining spaced discharge terminals, a rock shaft mounted in said coupling at the junction of the discharge terminals, a tank connected with the coupling and in communication with the 95 upper end of the same, a crank on the inner end of the rock shaft within the tank, clamping plates secured to said crank, a float arm secured by and between the clamping plates, and floats carried by said arm in 100 vertically spaced relation.

6. In an automatic cut-off for cisterns, the combination of a Y coupling having its upper end connected with a down spout and 105 having its lower end defining spaced discharge terminals, a rock shaft mounted in the coupling at the junction of the discharge terminals, a tank connected with the coupling and in communication with the upper end of the same, a crank on the inner end 110 of the rock shaft within the tank, clamping plates secured to said crank and having notches in their edges remote from the crank, a float arm having a central portion fitting between the clamping plates and 115 having diverging end portions, one of which passes through the notch in a clamping plate, and floats carried by the ends of the diverging portions of the said arm, the floats being disposed in vertically spaced relation. 120

In testimony whereof I affix my signature.
MAX E. CRANDALL. [L. s.]
